CLAIM

The ornamental design for a shoe, as shown and described.

DESCRIPTION

FIG. 1 is a top, left, front perspective view of an ornamental design for a shoe;

FIG. 2 is a bottom, right perspective view of the shoe of FIG. 1;

FIG. 3 is a front elevation view of the shoe of FIG. 1;
FIG. 4 is a rear elevation view of the shoe of FIG. 1; and,
FIG. 5 is a right side elevation view of the shoe of FIG. 1.
The dash-dash-dash broken lines are included for the purpose of illustrating portions of the shoe that form no part of the claimed design.**1 Claim, 5 Drawing Sheets**(56)
